FIG. 1 is a front elevational view of a garment top with a control layer;
 FIG. 2 is a rear elevational view thereof;

FIG. 3 is a right side elevational view thereof;
 FIG. 4 is a left side elevational view thereof;
 FIG. 5 is a top elevational view thereof;
 FIG. 6 is a bottom elevational view thereof;

FIG. 7 is a front elevational view of a garment top with a control layer, wherein the top has been turned inside-out;
 FIG. 8 is a rear elevational view thereof;
 FIG. 9 is a right side elevational view thereof;
 FIG. 10 is a left side elevational view thereof;
 FIG. 11 is a top elevational view thereof; and,
 FIG. 12 is a bottom elevational view thereof.
